UNITED STATES PATENT OFFICE.

JAMES O. PATTY, OF CHICAGO, ILLINOIS.

FOUNTAIN BRUSH.

Application filed April 6, 1923. Serial No. 630,198.

To all whom it may concern:

Be it known that I, JAMES O. PATTY, a citizen of the United States, and a resident of the city of Chicago, in the county of Cook 5 and State of Illinois, have invented certain new and useful Improvements in a Fountain Brush; and I do hereby declare that the following is a full, clear, and exact description of the same, reference being had to the accompanying drawings, and to the numerals of reference marked thereon, which form a part of this specification.

This invention relates to a combined soap dispensing and fountain brush particularly 15 suited for dish washing purposes and the like, but also equally applicable to other purposes such as vehicle body washing wherein it is customary to first go over the surface with a soapy solution and then to 20 rinse with clear water as in dish washing.

Heretofore, fountain brushes of various sorts have been proposed and dish mops carrying a bag of soap in conjunction therewith have also been marketed, but the combination of means for applying a soapy solution or a clear water rinse at the will of the operator and from the same instrument is believed to be entirely novel. The present 25 invention is intended to produce a practical and inexpensive means of combining a soap dispensing means with a fountain brush.

It is an important object of this invention to intermittently or continuously supply soap solution to a fountain brush in quantities graduated to suit the will of the operator.

It is a further important object of this invention to provide means for the formation of a soapy solution at the instant it is to be 40 used and in the exact quantity desired in order to conserve the supply of soap or other cleansing substance.

It is still a further important object of this invention to provide a scouring brush 45 for washing purposes having an adjustable running water connection adapted to either supply clear or soapy water or any intermediate mixture in the proportions desired.

It is another object of this invention to 50 supply a simple easily constructed and readily controlled device of the class described that can be manufactured in large quantities at a cost enabling the sale thereof at a very reasonable price.

55 Other and further important objects of

the invention will be apparent from the disclosures in the specification and drawings.

The invention (in a preferred form) is illustrated in the drawings and hereinafter more fully described.

On the drawings:

Figure 1 is a side view on a small scale of a device embodying one form of this invention.

Figure 2 is an enlarged bottom view of a 65 device similar to that shown in Figure 1.

Figure 3 is an enlarged section of a device corresponding to that of Figure 1.

Figure 4 is a section on the line 4—4 of Figure 3.

Figure 5 is a fragmentary sectional view of a modified form of water control valve.

Figure 6 is a section on the line 6—6 of Figure 5.

As shown on the drawings:

The reference numeral 1 refers to a handle which in the illustration is simply a common wooden handle screwed onto a passaged body member 2 containing suitable holding means 3 adjacent the lower part 80 thereof for a bristle brush having a twisted wire core 5 which is bent into a U-shape, the ends of the wires 5 being secured in suitable apertures in the holding means by common set or clamp screws 6. It is to be noted that a mop or cloth brush would be equally satisfactory as compared with a bristle brush for certain purposes, such as dish washing, and I do not desire to be limited to the specific construction of brush here shown, which 90 is a form well known in the prior art.

The body member 2 comprises an upstanding boss 7 for the attachment of a water supply hose 8; an aperture 9 leading through said boss and continuing into the body member and having branch passages 10 and 11; the passage 10 having a sliding sleeve valve 12 therein operated by a knob 24 and adapted when in the position shown in Figure 3 to admit water to the passage 10 in a 100 boss 13 connected to a receptacle or box 14 having a suitable removable cover 15. This box is disposed above the brush 4 and has a plurality of small apertures 16 in the bottom thereof to discharge the soapy solution directly upon the brush. A pair of ribs 17 are arranged within the box to prevent the cake of soap or other soluble cleaning agent therein from blocking or clogging the apertures 16. A stud 18 and wing nut 110

19 are arranged to hold the box cover in place.

Centrally disposed between the arms of the brush is a tube 20 communicating with the end of the passage 11 and having a plurality of apertures 21 in the plane of the brush adapted to spray clear water onto the brush when the valve 12 controlling the movement of the water is in a proper position.

The modification of Figures 5 and 6 differs from the foregoing only in the form of the sleeve valve 12^a which in this case is rotary and coaxial with the passage 9 and is rotated by a handle 22 projecting through a slot 23 in the wall of the boss 7 to cause the desired diversion of the water supply to the soap box through the port 25 therein.

The operation of the device of this invention is comparatively simple; a hose 8 is connected to a source of hot or cold water supply and a supply of a soluble cleaning agent such as scraps or a cake of soap is placed in the box 14 and the cover replaced. With the valve 12 in the position shown in Figures 3 and 6, the water, preferably under a gentle pressure, enters the soap box, becomes a soapy solution therein, and is sprayed onto the brush 4 through the apertures 16 with sufficient pressure to assure a maintenance of the spray even with the whole device turned over to scrub an inverted or inclined surface. With the valves as shown, the passage to the lower or clear water spray tube 20 is completely obstructed except for immaterial leakage around the valve.

In Figure 3, pushing the valve knob 24 to the left moves the valve 12 correspondingly and a full movement causes a complete shutting off of water to the soap box 14 and at the same time opens the passage to

the lower spray tube 20 so that the water is sprayed onto the brush 4 through the apertures 21 in a manner calculated to rinse the object being cleaned after an application of soap. In Figures 5 and 6, a rotation of the valve handle 22 causes the port 25 of the valve 12^a to close and a lower port to register with the passage 11 to produce exactly the same results as in the sliding valve.

It will be evident that no waste of soap occurs when rinsing articles as the water is shut off from the soap box. Further a very nice graduation of the amount of soap used is possible because of the range of adjustment from all soap to all rinse water.

I am aware that numerous details of construction may be varied through a wide range without departing from the principles of this invention, and I therefore do not purpose limiting the patent granted, otherwise than necessitated by the prior art.

I claim as my invention:

A fountain brush, comprising a hollow body member, a water supply connected thereto, a U-shaped brush connected thereto at an angle, a perforated pipe connected to the interior of said body member and disposed between the arms of said brush and in the plane thereof to discharge water over the whole interior brush surface, a soap box also connected to the interior of said body member, disposed parallel with said brush and perforated to discharge its contents on said brush, and a valve in said body member for controlling the flow of water to said pipe and soap box, said valve adapted for exclusive discharge of water to either the pipe or the soap box or for conjointly discharging to both.

In testimony whereof I have hereunto subscribed my name.

JAMES O. PATTY.
